LOWER RAIL FOR VENETIAN BLINDS

Filed Nov. 12, 1946

By Chas. Silver Attorney

UNITED STATES PATENT OFFICE

2,502,028

LOWER RAIL FOR VENETIAN BLINDS

Harry S. Rosenbaum, Baltimore, Md.

Application November 12, 1946, Serial No. 709,174

4 Claims. (Cl. 160—178)

1

This invention relates to Venetian blinds with particular reference to a novel construction of a bottom rail for such blinds.

Among the objects of this invention is the provision of a bottom rail structure of ornamental and attractive appearance which permits convenient, ready and simple attachment to the slot supporting tapes and the cords from which the Venetian blind is suspended without use of external attaching means, such as tacks, and without necessitating the employment of tools for the assembling.

Other, further and more specific objects of this invention will become readily apparent to persons skilled in the art from a consideration of the following description when taken in conjunction with the accompanying drawing wherein:

Fig. 1 is a perspective view of the bottom rail, resting in inverted position.

Fig. 2 is a cross-section along line 2—2 of Fig. 1, and in inverted position with reference thereto.

Fig. 3 is a fragmental section through a portion of a Venetian blind showing my improved bottom rail in relation to the tapes, cords and slats of the blind.

Fig. 4 is a fragmental section along line 4—4 of Fig. 2.

Fig. 5 is a fragmental section along line 5—5 of Fig. 3.

Fig. 6 is a perspective view of the novel clasp or fastening plate employed with my invention.

The main portion of the rail comprises the elongated channel 2, preferably of metal and polygonal section. This channel is connected to the cover 4 by the overlaps 6 on the flanges 8. At each end of the bottom rail, the channel contains the perforations 10 which are in substantial alignment with corresponding perforations 12 in the cover 4. As well known in the art, this end construction permits the attachment of a retaining cord to steady and thus prevent undue swaying of the blind.

The bottom rail is provided with a plurality of clasps or fastening plates 14, conforming in section closely to that of the channel 2. This clasp is provided with one or more hooks 16 and one or more inner protuberances 18. These hooks 16 are adapted to enter spaced slots 20 in the side 22 of the channel 2 when the plate is attached to the rail, while the protuberances 18 enter the bores 24 in the side 26 of the channel 2 when the plate is pressed into clasping position against the rail. The plate 14 is formed with a central raised area 28, thus providing a defined passageway between plate and rail when the outer

2

portions 30 of the plate rest directly against the rail in clasping position. This passageway or clearance is of a depth to accommodate the tape 32 of the blind while holding this tape in secure position.

The cover 4 contains the perforations 34 preferably along its longitudinal axis and equally spaced from the slots 20 in the channel 2. The channel 2 contains perforations 36 which are slightly larger than perforations 34 and in substantial alignment therewith. By this arrangement, lift cord 38 can be readily passed through perforations 34 and 36 and the end of cord 38 then knotted. The knot will pass through larger perforation 36 but will not pass through perforation 34, thereby affording a support for the bottom rail. The slats 40 and the cross ladder tapes 42, shown in Fig. 3, may be any of the ordinary types employed in Venetian blinds.

20 My novel lower rail construction admits ready application thereof to Venetian blinds, particularly where the tapes are in loop form. The seam or line of attachment of the tapes to each other is concealed by the fastening plate.

25 In using my device, the cords 38 are first passed through the perforations 34 and 36 of the cover 4 and channel 2, respectively, the ends of the cords are then knotted and the knot are drawn through perforations 36. Each loop tape 32 is then placed over the bottom of channel 2 so that the middle of each tape is over the corresponding perforation 36. The hooks 16 of the plates 14 are then inserted in the slats 20 of the channel 2, the tapes 32 being held between the hooks 16 which serve as guides to center the tapes. By pressing each clasp against the channel, the protuberances 18 will enter the perforations 26, and each tape 32 will lie between the raised portion 28 of the clasp and the channel portion of the rail. The tapes will be firmly held by clasps and the lines of junction between parts of the tapes will be covered.

30 This construction presents a very neat appearance and is also highly efficient in retaining the rail and tapes in proper relation to each other. The lower rail may be readily disassembled by prying against the edge 44 of each plate 14 upwardly, which will disengage the protuberances 18 from the perforations 26 and permit removal 50 of the clasps or plates 14. The looped tape 32 may then be slid away from lower rail.

35 My lower rail including clasps is preferably formed entirely of metal. However, part or all of the rail including the clasps may be replaced 55 by other material, such as plastics. When made

of metal, the end closure **46** of the rail is preferably integral with the cover **4**. By providing appendages on each end of the cover **4** of configuration corresponding to the cross-section of the channel **2** and bending these appendages at right angles to the cover **4**, the end closure will rest between the channel **2** and the cover **4** and provide a neat finish to the rail.

In lieu of the bores **24** in the side **26** of the channel **2**, indentations or other form of recess for receiving the protuberances may be substituted.

My invention is also adapted for the use of channels having cross-sections of other configurations than that shown in the drawing; for example, arcs, undulations, etc.

The present invention is not limited to the specific details set forth in the foregoing examples which should be construed as illustrative and not by way of limitation, and in view of the numerous modifications which may be effected therein without departing from the spirit and scope of this invention, it is desired that only such limitations be imposed as are indicated in the appended claims.

I claim as my invention:

1. In a rail for a Venetian blind, an elongated channel, a cover connected to said channel and a fastening plate for holding tapes carried by the blind securely to the rail, said fastening plate having a cross-section closely conforming to the outer contour of the channel, said plate having a plurality of hooks at one end and a plurality of inner protuberances near the other end and said plate having an intermediate raised portion between lower side portions, the lower side portions being adapted for contact with the channel when the plate is in fastening position and the raised portion being spaced from the channel when the plate is in said fastening position in amount to receive and hold fast the tapes carried by the blind, and said channel having openings on one side to receive the hooks on said plate when the plate is in fastening position.

2. In a rail for a Venetian blind, an elongated channel, a cover connected to said channel and a fastening plate for holding tapes carried by the blind securely to the rail, said fastening plate having a cross-section closely conforming to the outer contour of the channel, said plate having a plurality of hooks at one end and a plurality of inner protuberances near the other end and said plate having an intermediate raised portion between lower side portions, the lower side portions being adapted for contact with the channel when the plate is in fastening position and the raised portion being spaced from the channel when the plate is in said fastening position in amount to receive and hold fast the tapes car-

ried by the blind, and said channel having openings on one side to receive the hooks on said plate and openings on the other side to receive the protuberances on said plate when the plate is in fastening position.

3. In a rail for a Venetian blind, an elongated channel, a cover connected to said channel and a fastening plate for holding tapes carried by the blind securely to the rail, said fastening plate having a cross-section closely conforming to the outer contour of the channel, said plate having an intermediate raised portion between lower side portions, the lower side portions being adapted for contact with the channel when the plate is in fastening position and the raised portion being spaced from the channel when the plate is in said fastening position in amount to receive and hold fast the tapes carried by the blind, and said plate having a hook on each lower side portion at one end and a protuberance on each lower side portion near the other end, and said channel having openings on one side to receive the hooks on said plate when the plate is in fastening position.
4. In a rail for a Venetian blind, an elongated channel, a cover connected to said channel and a fastening plate for holding tapes carried by the blind securely to the rail, said fastening plate having a cross-section closely conforming to the outer contour of the channel, said plate having an intermediate raised portion between lower side portions, the lower side portions being adapted for contact with the channel when the plate is in fastening position and the raised portion being spaced from the channel when the plate is in said fastening position in amount to receive and hold fast the tapes carried by the blind, and said plate having a hook on each lower side portion at one end and a protuberance on each lower side portion near the other end, and said channel having openings on one side to receive the hooks on said plate and openings on the other side to receive the protuberances on said plate when the plate is in fastening position.
